UNITED STATES PATENT OFFICE.

HERBERT ALFRED HUMPHREY, OF WESTMINSTER, LONDON, ENGLAND, ASSIGNOR TO
HUMPHREY GAS PUMP COMPANY, A CORPORATION OF NEW YORK.

METHOD OF RAISING AND FORCING LIQUIDS.

1,243,297.

Specification of Letters Patent. Patented Oct. 16, 1917.

Application filed March 31, 1911, Serial No. 618,242. Renewed February 9, 1917. Serial No. 147,722.

To all whom it may concern:

Be it known that I, HERBERT ALFRED HUMPHREY, a subject of the King of England, residing at 38 Victoria street, Westminster, in the county of London, England, consulting engineer, have invented certain new and useful Improvements in Methods of Raising and Forcing Liquids, of which the following is a specification.

10 My invention relates to improvements in the method of moving liquid by an expansive force. The purpose of the present invention is to provide an improved method whereby is secured an exact definite expandable charge for each cycle of operation, and whereby the amount of said charge may be varied at will.

Referring to the drawings which illustrate, merely by way of example, suitable 20 means for effecting my improved method—

Figure 1 is a diagrammatic vertical section of apparatus for effecting the method herein described.

Fig. 2 is a vertical section on an enlarged 25 scale of the upper part of an expansion chamber, showing valves and valve control.

Fig. 3 is a plan view of same.

Fig. 4 is a diagrammatic vertical section of a modification of said apparatus.

30 Fig. 5 is a sectional detail of pressure controlling mechanism for regulating liquid supply.

Similar numerals refer to similar parts throughout the several views.

35 Fig. 1 shows the application of the invention to the type of internal combustion pump having a suction lift in addition to a forced lift. 1 is the combustion chamber, 2 is a valve which gives communication to 40 the supply liquid which is to be raised from a level a through the suction pipe 3 and delivered through the discharge pipe 4 to the elevated tank 5. Valves 6 and 7 are the usual exhaust valve for burnt products and 45 admission valve for combustible charges, but in the present case there is an additional valve 8 which controls communication between chamber 1 and a reservoir 10 through a pipe 9 which projects downwardly into chamber 1. The mechanism which controls 50 the valves 6, 7 and 8, is such that valve 6 opens at one part of the cycle, while valves 7 and 8 remain shut, and the last mentioned valves open during another part of the cycle 55 when valve 6 remains shut. A suitable mechanism for controlling the valves will be described hereinafter.

In describing the cycle it will be assumed that there is a compressed combustible charge in the top of chamber 1 which 60 charge, when it was at about atmospheric pressure, occupied the top of the combustion chamber above the level of valve 8, and that valves 2, 6, 7 and 8 are all closed. Ignition occurs and the liquid in chamber 1 65 is driven downward setting the column of liquid in pipe 4 in motion so that it gains velocity. When expansion has been carried to about atmospheric pressure in chamber 1 the exhaust valve 6 opens under its own 70 weight but valves 7 and 8 remain locked shut. The liquid column is now moving in pipe 4 with considerable velocity and the further downward movement of the liquid in chamber 1 creates a partial vacuum there- 75 in sufficient to cause valve 2 to open and liquid to be drawn through pipe 3 until the energy of the moving column is expended, the liquid in pipe 4 comes to rest, and valve 2 closes under its own weight. Non-return 80 valve 11^a in the exhaust pipe prevents burnt gases being drawn into chamber 1 during the part of the cycle last described. A return movement of the column of liquid toward the combustion chamber now begins 85 due to the head or pressure to which the liquid has been raised or forced, and to the partial vacuum in chamber 1. Liquid rising in the combustion chamber expels products of combustion through exhaust valve 6 and 90 non-return valve 11^a until the liquid having gained velocity and reached valve 6 shuts this valve in the usual way and compresses an elastic cushion in the space above this valve. The cushion expansion stroke now occurs, 95 causing the second outward movement of the liquid column and the intake of a combustible charge through valve 8, which may open under its own weight when the pressure is low enough, and also through valve 100 7, which opens against the action of its spring. If there were no frictional or other losses the cushion expansion stroke would be followed by an intake of combustible mixture until the level of liquid in chamber 105 1 was again that at which the beginning of the first instroke occurred, when the column of liquid would come to rest and valve 7 would shut under the action of its spring. Owing, however, to frictional and other 110

losses the level of liquid does not fall so far, but none the less the volume of combustible mixture thus drawn into chamber 1 exceeds the volume of the charge last ignited, which at approximately atmospheric pressure occupied the space in the combustion chamber above the level of valve 8. It is therefore necessary to reject the surplus mixture, and this is accomplished when the 10 second inward movement of the liquid column occurs, for valve 8 remains open to allow the surplus mixture to be discharged through pipe 9 into reservoir 10, as the liquid rises in chamber 1. When the liquid 15 reaches valve 8, it shuts this valve, and the continued movement of the column of liquid compresses the correct volume of combustible mixture in the top of chamber 1 ready for ignition to start a fresh cycle.

20 If reservoir 10 is a closed vessel the entrance of the surplus mixture will slightly raise the pressure in reservoir 10 and this additional pressure will remain till valve 8 opens again in the next cycle. There will 25 in consequence be a tendency, when the next admission stroke occurs, for the surplus mixture to escape past valve 8 into the combustion chamber before valve 7 opens against the action of its light spring. Then 30 when valve 7 opens the additional quantity of mixture is taken in. It will thus be seen that for normal steady working of the apparatus a certain volume of mixture enters and leaves chamber 10 at each cycle and the 35 correct working charge is supplied through valve 7 at each cycle.

Describing next the gear, shown in Figs. 2 and 3; on the stems of the valves 6, 7 and 8 are nuts 11, 12 and 13 respectively, recessed as shown, so that a rotating bolt pivoted at 14 and having three arms 15, 16 and 17, adapted to enter the recesses, may, when in one position, lock valves 7 and 8 shut.

45 On a pivot 22 carried by the bridge piece 18 turns a lever having three arms 19, 20 and 21. This lever is retained in either of its extreme positions by the spring 23 which tends to increase the distance between the pivot 24, fixed to a stationary part, and the pivot 25 fixed to the lever as shown.

With the parts in the positions shown, the exhaust valve 6 is open and the non-return valve 11^a, which is here shown as sliding loosely on the stem of valve 6, is closed so that the positions are correct for the working stroke in chamber 1. On the first inward movement of the liquid column, valve 11^a will be lifted as soon as the pressure of the gases in chamber 1 is slightly above atmospheric pressure, and the burnt gases will be discharged past valve 6 until this valve is shut by the action of the liquid. Until this occurs the end of arm 15 is 65 pressed against the non-recessed portion of

nut 11, for the reason that, of the two springs 26 and 27, which are attached between 21 and the two projections 28 and 29 upon the rotating bolt, spring 26 is under greater tension than spring 27, owing to 70 21 leading to the left of the vertical position.

As soon however, as valve 6 shuts, spring 26 urges the end of 15 into the recess of nut 11 and locks valve 6 shut. The movements of the rotating bolt at the same time release arms 16 and 17 from the recesses of nuts 12 and 13, so that valves 7 and 8 are free to open when pressure in chamber 1 is low enough. When the admission stroke 80 occurs and valve 7 opens, nut 12 engages arm 20, and turns the three armed lever into its other extreme position, so that arm 21 is now on the right hand side of the pivot 22 and puts tension on spring 27, while relieving that on spring 26. The rotating bolt is now urged to the right, and when valves 7 and 8 are shut, the arms 16 and 17 engage in the recesses of the nuts 12 and 13 and so lock the two valves shut and at the 90 same time release valve 6.

In Fig. 2 valve 7 is shown with a double seat, with the object of admitting air through the annular space 29, and gas through the pipe 30 in such a manner that 95 valve 7 controls the admission of both constituents.

It is sometimes advantageous to substitute for the valve 7, at the top of the combustion chamber, a similar valve attached to the reservoir 10, as for instance on a branch 31, so as to admit combustible mixture into the reservoir 10. In such a case the working charge, as well as the surplus combustible mixture, will pass through pipe 9 and valve 8 into the chamber, on each admission stroke, and valves 6 and 8 will be mutually controlled in the same way as has just been described for valves 6 and 7. Valve 7 is then independent of any controlling mechanism and simply opens under suction against the action of its light spring.

By making the pipes, which are respectively controlled by valves 6 and 8, adjustable vertically with reference to the combustion chamber 1, the flexibility of the apparatus is greatly increased. It will be seen that if the position of valve 8 is lowered with respect to the top of chamber 1, by moving pipe 9 vertically downward in the 120 chamber, then the amount of combustible charge retained for the working stroke is increased. It is then desirable to increase the cushion space above valve 6 by lowering the exhaust pipe in chamber 1. If these 125 two changes are made the conditions are correct for an increased output per working stroke.

Should the amount of liquid oscillating in pipe 4 become lessened by waste or other 130

cause, the amount of combustible mixture taken into chamber 1 will be increased thus increasing the amount of surplus charge to be rejected. It is very desirable that the amount of charge rejected should remain approximately constant, and this can be accomplished by regulating a supply of liquid to pipe 4 by the simple device shown in Fig. 5, where a portion of the chamber 1 and pipe 4 are shown connected with a pipe 40, capable of supplying liquid under pressure through cock 41 and non-return valve 42. Opening into reservoir 10 is a barrel 43 in which slides a piston 44 attached to a rod 50 having at its other end a pin 51 engaging in a slot 52 of a lever 53 which controls the position of cock 41. A spring 54 urges the piston 44 to the left, in which position the lever 53 closes the cock 41. At each cycle the rejected charge, entering reservoir 10, increases the pressure therein, and this increase of pressure acting upon piston 44 urges the rod 50 and lever 53 to the right against the action of spring 54, thus tending to open cock 41. The adjustment of these parts may be such, that any excess of pressure in chamber 10, above a desired amount, will open cock 41 for a portion of each cycle and thus allow liquid to be supplied to increase the volume of the oscillating column in pipe 4 until the amount of rejected charge is thereby decreased and the rise of pressure in chamber 10 is no longer sufficient to cause the piston 44 to open the cock 41 for a portion of each cycle. By this means the rise of pressure in reservoir 10 can be made approximately constant or, in other words, the amount of charge rejected each cycle remains approximately the same.

If the pressure of supply in pipe 40 is high enough valve 42 may be omitted, then by making the cock 41 a two-way cock the motion of lever 53 can be made either to permit liquid to flow through pipe 40 into pipe 4 or to discharge liquid from pipe 4 to waste, and by such an arrangement the pressure in chamber 10 may be prevented from falling below a definite amount as well as from rising above a desired amount.

What I claim is:—

- 50 1. The method which consists in reciprocating a liquid, the first outstroke being due to an expansive force, entraining an expandable charge in excess of amount required, by one movement of the reciprocating liquid, expelling the excess of said charge and compressing the remaining charge by a return movement of said liquid.
- 60 2. The method which consists in reciprocating a liquid, the first outstroke being due to an expansive force, entraining a combustible charge in excess of amount required, by one movement of the liquid, expelling the excess of said charge and compressing the remaining charge by a return movement of

the liquid, confining the expelled excesses of charge and utilizing the same in connection with subsequent charges.

3. The method which consists in reciprocating a liquid, the first outstroke being due to an expansive force, entraining a combustible charge in excess of amount required, by one movement of the liquid, expelling the excess of said charge and compressing the remaining charge by a return movement of the liquid, confining under pressure the expelled excesses of charge and utilizing the same in connection with subsequent charges.

4. The method which consists in reciprocating a liquid, the first outstroke being due to an expansive force, entraining an expandable charge in excess of amount required, by one movement of the liquid, expelling by a return movement of the liquid, the excess of said charge and thereby causing an increase of pressure in order to discharge like volumes at subsequent cycles.

5. The method which consists in reciprocating a liquid, the first outstroke being due to an expansive force, entraining an expandable charge in excess of amount required, by one movement of the liquid, expelling by a return movement of the liquid, the excess of said charge and thereby causing an increase of pressure, in order to discharge like volumes at subsequent cycles, and controlling, by said increase of pressure, the amount of liquid reciprocated.

6. The method which consists in reciprocating a liquid, the first outstroke being due to an expansive force, entraining an expandable charge in excess of amount required, by one movement of the liquid, expelling by a return movement of the liquid, the excess of said charge into a reservoir, thereby causing an increase of pressure in order to discharge like volumes at subsequent cycles, and controlling, by said increase of pressure a supply to liquid acted upon by the expansive charge.

7. The method which consists in reciprocating a liquid, the first outstroke being due to an expansive force, entraining an expandable charge, in excess of amount required, by one movement of the liquid, expelling by a return movement of the liquid, the excess of said charge and compressing the remaining charge.

8. The method which consists in reciprocating a liquid, the first outstroke being due to an expansive force, a return stroke being due to pressure or head of liquid resulting from the outstroke, utilizing said return stroke to expel exhaust products and compress an elastic cushion, utilizing the expansion of said cushion to cause a second out-stroke, entraining a fresh expandable charge in excess of amount required, by one movement of the liquid, expelling the excess of said charge and compressing the remain-

ing charge by a return movement of the liquid.

9. The method which consists in reciprocating a liquid, the first outstroke being due 5 to an expansive force, a return stroke being due to pressure or head of liquid resulting from the outstroke, utilizing said return stroke to expel exhaust products and compress an elastic cushion, utilizing the expansion 10 of said cushion to cause a second outstroke, varying the volume of the elastic cushion, entraining a fresh expansible charge in excess of amount required, by one movement of the liquid, expelling the excess 15 of said charge and compressing the remaining charge by a return movement of the liquid.

10. The method which consists in reciprocating liquid, the first outstroke being due 20 to an expansive force, entraining an excessive expansible charge by one movement of the reciprocating liquid, expelling by a return movement of the liquid the excess of said charge into a supply, thereby causing 25 an increase of pressure of the supply.

11. The method which consists in reciprocating liquid, the first outstroke being due to an expansive force, entraining an excessive expansible charge by one movement of the reciprocating liquid, expelling the excess of said charge by a return movement of the liquid adapted to confine the balance of the charge.

12. The method which consists in reciprocating liquid, the first outstroke being due 35 to an expansive force, entraining an excessive expansible charge by one movement of the reciprocating liquid, expelling the excess of said charge by a return movement 40 of the liquid adapted to confine the balance of the charge and varying the amount of charge confined.

13. The method which consists in recip-

rocating liquid, the first outstroke being due to an expansive force, a return stroke being due to pressure or head of liquid resulting from the outstroke, utilizing said return stroke to expel a portion of the exhaust products and then to compress an elastic cushion, utilizing the expansion of the elastic cushion to cause a second outstroke to entrain an excessive expansible charge, expelling the excess of said charge, and compressing the remaining charge by a return movement of the liquid, and varying the volume of elastic cushion compressed. 45 50 55

14. The method which consists in reciprocating liquid, the first outstroke being due to an expansive force, entraining an excessive expansible charge by said outstroke, utilizing the movement of the outstroke to discharge a portion and to compress the balance of an elastic cushion, utilizing the movement of the liquid in the return stroke to expel the excess of the expansible charge 60 65 and then to confine and compress the balance of said discharge adjusting the amount of charge confined and compressed.

15. The method which consists in reciprocating a liquid of sufficient volume and 70 path of travel to acquire useful momentum, the first outstroke being due to an expansive force, entraining an excessive expansible charge by one movement of the liquid, expelling the excess of said charge, compressing the remaining charge by a return movement of the liquid, and varying the volume of charge compressed. 75

In testimony whereof I have signed my name to this specification in the presence 80 of two subscribing witnesses.

HERBERT ALFRED HUMPHREY.
